UNITED STATES PATENT OFFICE.

50 LUTHER L. KNOX, OF BEN AVON, AND MONTGOMERY MURRAY, OF WILKINSBURG, PENN-
SYLVANIA, ASSIGNEES TO KEYSTONE FURNACE CONSTRUCTION COMPANY, OF PITTS-
BURG, PENNSYLVANIA, A CORPORATION OF PENNSYLVANIA.

FURNACE.

55 00 No. 919,188.

Specification of Letters Patent. Patented April 20, 1908.

Original application filed February 17, 1908, Serial No. 416,185. Divided and this application filed July 8, 1908.
Serial No. 442,455.

60 00 To all whom it may concern:

Be it known that we, LUTHER L. KNOX, of Ben Avon, Allegheny county, Pennsylvania, and MONTGOMERY MURRAY, of Wilkinsburg, Allegheny county, Pennsylvania, have invented a new and useful Improvement in Furnaces, of which the following is a full, clear, and exact description, reference being had to the accompanying drawings, forming 10 part of this specification, in which—

Figure 1 is an end view of one form of furnace embodying our invention; Fig. 2 is a horizontal section of the same taken on the line II—II of Fig. 3; Fig. 3 is a vertical section taken on the line III—III of Fig. 1; and Fig. 4 is a detail view of one of the cooling boxes.

Our invention has relation to regenerative reversing furnaces, and more particularly to open hearth furnaces, and is designed to provide means of an improved and effective character for protecting the gas and air ports of the furnace from the destructive action of the heat and hot gases, and relates more particularly to a novel arrangement of cooling plates or boxes in the walls of the gas and air ports, and to the construction of the arch which separates the gas and air ports and to the manner of cooling the same.

The present application is a division of our application Serial No. 416,185, filed February 17th, 1908.

The precise nature of our invention will be best understood by reference to the accompanying drawings, in which we have shown one embodiment thereof, and which will now be described, it being premised, however, that various changes may be made therein by those skilled in the art without departing 40 from the spirit and scope of our invention, as defined in the appended claims.

In these drawings, the numeral 2 designates the walls of an open hearth furnace, which is in general of ordinary construction. 45 3 designates a portion of the furnace hearth, 4 designates the gas up-takes, and 5 the air up-takes.

In the furnace shown, there are two gas up-takes and three air up-takes, but my invention is not limited to any particular number of these up-takes, since a single gas up-take and a single air up-take may be employed, or any other desired number, ac-

cording to the size and character of the furnace. These up-takes are separated from each other by the intermediate walls or piers 6. The gas up-takes communicate with the furnace chamber at their upper ends by means of the gas ports 7, and the air up-takes communicate with said chamber by 60 means of the air ports 8.

9 designates the arch over the gas ports. This arch is of refractory material, and is built as an integral part of the walls of the ports, and is cooled by means of the hollow 65 cooling plates or boxes 10 and 10' embedded therein. These boxes are inserted into the arch into chambers therein provided therefor within the refractory material of the arch through openings 11 in the side wall of the 70 furnace in the manner shown in Fig. 2, their inner ends being preferably separated from each other by an intervening wall 12. The boxes 10 are provided with the circulating connections 13 and 14, and with the interior 75 baffles 15, which provide for proper circulation of the water therein. The boxes 10' are provided with the valve circulating connections 16, and are divided into a plurality of separate compartments as shown in Fig. 80 2, each compartment having its own circulating connections. In this manner, should the compartment nearest to the nose of the arch become burned out, the water may be shut out of that compartment, and so on 85 until the arch is burned back to the last compartment of the boxes 10'. We also preferably place in each of the intervening walls or piers, between the gas and air ports a cooling box or plate 17, which is inserted 90 into an opening into a chamber to receive the same from the end of the furnace. These cooling boxes 17 (one of which is shown in detail in Fig. 4) extend inwardly to the point where the gas ports discharge into the furnace, and effectively protect the side walls 95 of these ports. We also preferably provide the bridge or arch 19, which constitutes the lower wall of the gas ports, with cooling boxes 20, 21, and 22, which are inserted 100 therein from the sides of the furnace, in a manner similar to the boxes 9 and 10. The front walls of the gas and air up-takes are also preferably provided with a plurality of water-cooling boxes 24, set into the brick 105 work thereof, these boxes being arranged in

series one above another between adjacent piers, in the manner shown in Fig. 1. Each vertical series of these boxes is connected by a pipe 25 with a supply pipe 26. The several boxes are connected in series, the upper box having an outlet connection 27. The various connections are provided with detachable unions, so that any box can be readily disconnected and removed and replaced, they being removably seated in the walls of the ports.

By means of our invention, the arches separating the gas and air ports, together with the walls of the ports which are most subject to the destructive action, are effectively protected. The cooling plates and boxes are readily accessible, and can be replaced and renewed when burned out. Our invention, therefore, greatly prolongs the life of the ports as a whole, and limits the renewals and repairs to the portions thereof which can be readily removed and replaced.

It will be obvious that our invention is not limited to the particular arrangement of cooling plates and boxes which we have herein shown and described, since these may be arranged in various ways. The circulating connections may also be changed, as may be most convenient in any particular case, and the construction and arrangement of the baffles in the interiors of the cooling boxes may also be varied. It will also be obvious that our invention is applicable to other forms of regenerative reversing furnaces.

We claim:—

1. In a furnace of the type described, having gas and air ports, an arch separating said ports, and hollow water-cooled boxes or plates extending into said arch and having separate compartments, together with means for shutting off the water-supply from one or more of the compartments; substantially as described.
2. In a furnace of the type described having gas and air ports, an arch separating said ports, hollow water-cooled boxes or castings removably seated within the said arch, and other water-cooled boxes seated in other walls of the ports; substantially as described.
3. In a furnace of the type described having gas and air ports, an arch separating said ports, hollow water-cooled boxes or castings removably seated in said arch, and remov-

able through openings at opposite sides of the furnace; substantially as described.

4. In a furnace of the character described having a gas port leading into the furnace, removable water-cooled boxes within the lower, inner and outer walls of said ports; substantially as described.

5. In a furnace of the character described having a gas port leading into the furnace, removable water-cooled boxes within the lower inner and outer walls of said port, said boxes being removably seated in said walls; substantially as described.

6. A furnace of the class described having a plurality of gas and air up-takes separated by piers, a plurality of removable water-cooled boxes in the end walls of said up-takes between the piers, and other water-cooled boxes removably seated in the piers; substantially as described.

7. A furnace of the class described having a plurality of gas and air up-takes, a plurality of water-cooled boxes in the end wall of each up-take, and other water-cooling boxes in the walls or piers separating the several up-takes; substantially as described.

8. In a furnace of the class described having gas and air ports, an arch of refractory material separating the gas and air ports and integrally connected with the walls of the furnace, and water-cooling boxes removably inclosed within said arch, said boxes being removable at the side of the furnace; substantially as described.

9. In a furnace of the class described having gas and air ports, an arch of refractory material separating the gas and air ports and integrally connected with the walls of the furnace, and water-cooling boxes removably inclosed within said arch, said boxes being removable at the side of the furnace and having a plurality of separate compartments and water-circulating connections therefor provided with means for shutting off the water supply from one or more of the compartments; substantially as described.

In testimony whereof, we have hereunto set our hands.

LUTHER L. KNOX.
MONTGOMERY MURRAY.
